UNITED STATES PATENT OFFICE.

SAMUEL R. HERRING, OF DELHI, LOUISIANA.

PLOW.

1,346,751.

Specification of Letters Patent. Patented July 13, 1920.

Application filed March 15, 1920. Serial No. 365,848.

To all whom it may concern:

Be it known that I, SAMUEL R. HERRING, a citizen of the United States, residing at Delhi, in the county of Richland and State 5 of Louisiana, have invented new and useful Improvements in Plows, of which the following is a specification.

The object of the invention is to provide a simple, inexpensive and efficient means 10 whereby a plow shovel or bit may be attached to a plow standard under such conditions as to permit of the removal thereof with facility while insuring the substantial holding of the same in operative position 15 when mounted without the use in their connection, as in the ordinary practice, of bolts and similar appliances which are more or less difficult of manipulation, requiring the use of tools, and which being subject to continual wear in the operation of the device 20 soon become inoperative or ineffective as a means of maintaining the blade in its proper position, and with these objects in view the invention consists in a construction and combination of parts of which a preferred embodiment is shown in the accompanying drawings, wherein:

Figure 1 is a side view of the plow.

Fig. 2 is a sectional view of the same taken 30 longitudinally.

Fig. 3 is a perspective view of one of the wear plates.

Fig. 4 is a plan view.

Fig. 5 is a transverse section on the plane 35 indicated by the line 5—5 of Fig. 1.

Fig. 6 is a detail view of the latch by means of which the operating bar is held in its shovel locking position.

Fig. 7 is a detail view of the locking bar. 40 Fig. 8 is a similar view of the clamp.

Supported by the usual plow beam 10 is a standard 11 held in place by means of transverse bolts 12 which extend transversely above and below the beam in contact with upper and lower wear plates 13 and 14, said standard being of looped form, consisting of the side members 15 which are spaced apart to form a guide for a clamp 16 which is pivotally mounted as at 17 upon 45 the standard and is provided at its forward end with a rearwardly turned jaw 18 adapted for engagement with an opening 19 in the plow blade or bit 20 arranged upon a seat 21 formed by the front edges of the 50 members of the standard adjacent to the looped portion thereof. The seat is prefer-

ably formed by cutting away a portion of the front edges of said members of the standard to provide a shoulder 22 which bears upon the upper edge of the blade or shovel so 60 that when the clamp is arranged in engaging relation therewith as indicated in Figs. 1 and 2, the cam faced or beveled inner side of the jaw of the clamp serves to crowd the blade upward with its edge against said shoulder to lock the same against displacement and vibration.

Connected with the projecting rear end of the clamp member is an operating bar 23 which extends upward through guide openings or slots 24 and 25 in said plates 14 and 13, and through a corresponding registering opening in the beam, and is provided at its upper end with a grip or handle 26 by which the bar may be pulled upward forcibly to cause a firm engagement of the clamp member with the plow shovel or blade.

The operating bar is adapted to be secured in its shovel locking position by means of a latch 27 pivotally mounted as at 28 upon the plow beam and having a nose 29 for engagement with either of a series of openings 30 in the bar, to suit the thickness of the shovel or blade.

It will be noted that when the clamp member is in its engaging position the nose or extremity of the jaw thereof after passing through the opening in the shovel or blade lies between the side members 15 of the standard, so as to brace the latter against 90 transverse displacement as in order to remove or substitute another blade or shovel it is simply necessary to disengage the latch from the operating bar and lower the latter so as to withdraw the jaw of the clamp member from its engagement with the shovel. Another blade may be inserted and clamped without inconvenience or loss of time and when engaged it is securely held against displacement.

Having described the invention what is claimed is:—

1. A plow having a standard provided at its lower end with a shovel or blade seat, a pivotal clamp member mounted upon the 105 standard and provided with a downwardly and rearwardly directed jaw for engagement with an opening in a shovel or blade engaging said seat, an operating bar connected with said clamp member and extending slidably through suitable guides on the plow beam, and a latch for engaging and 110

securing said operating bar with the clamp member in its shovel engaging position.

2. A plow having a looped standard provided with a shovel or blade seat, a clamp 5 pivotally mounted upon said standard above and in rear of the seat and provided with a downwardly and rearwardly directed jaw for engaging an opening in a shovel or blade arranged upon said seat, an operating bar 10 connected with the rear end of said clamp member and extending upwardly through

guides on the plow beam, said bar being provided with a plurality of openings, for exposure above the plow beam, and a latch pivotally mounted upon the plow beam and 15 having a nose bearing upon the upper side thereof for engagement with one of said openings in the operating bar for securing the latter with the clamp member in its shovel or blade engaging position. 20

In testimony whereof I affix my signature.
SAMUEL R. HERRING.
